Primary Examiner—Jennifer Rivard(74) Attorney, Agent, or Firm—Dergosits & Noah LLP(57) CLAIM

The ornamental design for a cosmetic container, as shown and described.

DESCRIPTION

FIG. 1 is a perspective view of a cosmetic container showing my new design;

FIG. 2 is a top view of the cosmetic container of FIG. 1; the bottom view being a mirror image thereof;

FIG. 3 is a front view of the cosmetic container of FIG. 1;

FIG. 4 is a back view of the cosmetic container of FIG. 1;

FIG. 5 is a side view of the cosmetic container of FIG. 1; and,

FIG. 6 is another perspective view of the cosmetic container of FIG. 1.

The broken line showing the interior of the container is included for the purpose of illustrating portions of the article and forms no part of the claimed design.
